CLAIM

I claim the ornamental design for a color coded racquet grip, substantially as shown and described.

DESCRIPTION

FIG. 1 is a perspective view of the color coded racquet grip according to my invention;

FIG. 2 is a plan view of the bottom end of the color coded racquet grip according to my invention;

FIG. 3 is yet another perspective view of the color coded racquet grip according to my invention;

FIG. 4 is an elevation view of one side of the color coded racquet grip according to my invention; and,

FIG. 5 is an elevation view of another side of the color coded racquet grip according to my invention.

The broken lines in the figures depict environmental subject matter and form no part of the claimed design.
